UNITED STATES PATENT OFFICE

JOHN FENTON, OF COLUMBUS, OHIO

CUSHIONED INSOLE

Application filed April 11, 1929. Serial No. 354,393.

This invention relates to shoes and more particularly to insoles for use in shoes and in its preferred form my invention forms a part of the shoe itself. The modern hard surface pavements produce a shock to the body when walking for which there is no provision in nature and in order to provide the comfort nature intended it is necessary to place a cushion in the soles of the shoes to receive the weight at the weight bearing points and to provide a shock absorbing medium at the vital points and thereby restore the proper form of contact for which the foot is adapted by nature.

It has been found that in walking or taking a step forward the entire weight of the body is sustained momentarily by the os calcis or heel bone, the heel being first to contact with the ground, the point of contact being below the lower rear portion of the os calcis. When a person stands erect on a hard level surface the weight of the body is transmitted through the feet to the pavement at three weight bearing points in each foot. These principal weight bearing points on the bottom of each foot are the area toward the inner rear portion of the heel which lies directly below the lowermost extending portion of the os calcis or heel bone, the area lying directly below the forward end of the first metatarsal bone and the area lying below the forward end of the fifth metatarsal bone. The weight bearing center in each foot is on the line extending from the center of the lowermost portion of the heel bone forwardly through the center of the forward end of the second metatarsal bone from which it will be seen that that portion of the weight which is distributed forward of the heel bone falls about equally on either side of the second metatarsal bone. It is obvious that when the foot contacts with the earth or soil those portions of the foot which have been designated the weight bearing points sink into the earth or soil and permit the other areas on the bottom of the

foot to contact and support the weight of the body. Since the principal weight bearing points are first to contact with the ground a provision was set up by nature whereby the entire supporting area of the foot did not contact until the principal weight bearing points had depressed the earth thereby absorbing the shock incident to walking.

The principal object of my invention resides in the provision of an insole having cushions at the principal weight bearing portions of the foot for absorbing the shock caused by contact with hard pavements, thereby eliminating the jar incident to walking.

A further object of my invention resides in the provision of an insole which will not wrinkle or creep and which retains all of the shock absorbing qualities usually found in cushion insoles, and rubber top lifts on heels.

A still further object of my invention is the provision of an insole which insures the correct weight distribution at the ball of the foot as well as insuring correct tread thereby relieving the toes from unnatural strain.

With these and other objects in view which will appear as the description proceeds, my invention consists in the novel features of construction, combinations of elements and arrangements of parts hereinafter to be fully described and pointed out in the appended claims.

In the accompanying drawings:

Figure 1 is a plan view of the insole comprising the present invention with the position of the bones of the foot indicated when the shoe is worn.

Figure 2 is a longitudinal sectional view of Figure 1 taken on the line 2—2,

Figure 3 is a detailed sectional view of a shoe embodying the present invention.

Referring more particularly to the drawings, the numeral 1 designates my improved insole in its entirety, which comprises a main body portion 2 which is formed preferably

from leather although other substances with similar non-resilient qualities may be employed. The body portion 2 is formed with openings to receive cushions 3 and 4. The 5 cushion 3 is formed preferably from soft spongy rubber, although other cushioning material may be employed such as felt, wool or fabric, and is positioned within an elliptical shaped opening in the heel portion of 10 the body 2. The cushion 4 is also formed preferably from soft spongy rubber and is positioned within the forward portion of a heart shaped opening in the forward portion of the body 2. Immediately adjoining 15 the cushion 4 and occupying the rear portion of the heart shaped opening is a supporting area 5 which is formed preferably from harder rubber which is pliable and of sufficient hardness to effect the support of the 20 area of the foot above. The cushions 3 and 4 are cemented to the edges of the openings in which they are placed and the supporting area 5 is likewise cemented to the edges of the opening in which it is placed, its forward edge being cemented to the rear edge of the cushion 4.

In constructing shoes employing my invention the upper 6 is lasted in place to the sole 7 by any of the well known methods. 30 The insole 1 is then cemented in place above the inner side of the sole 7, as shown in Figure 3, after which the soles 1 and 7 may be sewed or otherwise fastened together in the usual manner. The heel portion of the insole 1 is then raised and the heel is attached after which the heel portion of the insole is cemented in place. It will thus be seen that the lasting tacks are completely covered up by the insole 1 leaving a smooth insole surface. 35 The upper surface of the insole 1 may then be covered with a sock lining 8 formed from thin leather or other suitable material and firmly cemented in place.

Referring to Figure 2 it will be seen that 40 the cushions 3 and 4 extend slightly above the upper surface of the body portion 2 but are formed preferably of soft resilient rubber that is capable of being compressed below the upper surface of the insole 1. It will 45 also be observed that the edges of the openings in the insole 1 are bevelled so that when the insole is applied the cushions 3 and 4 extend above the lower edges of the openings thus insuring a flexible meeting edge.

Referring to Figure 1 it will be observed 50 that when the shoe is worn the inner rear portion 9 of the os calcis 10 will be directly above the cushion 3. It is that portion of the foot immediately below the rear portion 55 9 which first contacts with the ground when walking. The position of the cushion 3 permits that portion of the heel, when the foot is planted, to first contact with the resilient rubber body which acts as a shock absorber 60 and provides the form of contact for which

the foot is by nature designed by permitting the principal weight bearing point at the heel to be yieldingly received in the resilient area provided in the insole and permitting the remainder of the heel area to contact properly with the non-resilient area of the heel portion of the insole. The cushion 4 is formed with a narrow middle portion 11 and circular shaped ends 12 and 13. It will be seen by reference to Figure 1 that the end 70 12 is positioned immediately below the forward end of the first metatarsal bone 14, the other end 13 being immediately below the forward end of the fifth metatarsal bone 15. The narrow or middle portion 11 joining the 75 two ends 12 and 13 lies below the second, third and fourth metatarsal bones and just to the rear of their forward ends. Since the principal weight bearing points of the ball of the foot are immediately below the forward end of the first metatarsal bone and the forward end of the fifth metatarsal bone, it will be seen that the cushion 4 is shaped and positioned to receive those weight bearing points. When weight is applied to the foot, 80 the weight bearing points will sink into the resilient ends 12 and 13 of the cushion 4 and permit the forward ends of the second, third and fourth metatarsal bones and the toes of the foot to correctly contact with the non-resilient portion 2 of the insole 1 at its forward portion. The middle portion 11 of the cushion 4 imparts to the insole the necessary 85 flexibility. It will be seen that the cushion 4 absorbs the shock at the principal weight bearing points at the ball of the foot and permits that portion of the foot when the weight is applied to contact in the manner for which it is by nature designed and compensates for the unyielding surfaces presented by the 90 modern pavement. It will also be noticed that while adequate cushioning is provided at all points, that portion of the insole 1 95 underneath the toes and underneath the forward ends of the second, third and fourth metatarsal bones is of non-resilient material 100 so that the toes are permitted to grip the shoe in lifting the body forward. Immediately to the rear of the cushion 4 is the support 5 which is triangular in shape and formed 105 preferably of relatively hard but flexible rubber. The support 5 extends under all of the metatarsal bones rearward of their forward ends and is so fashioned that when weight is applied to the foot two of the principal weight bearing points sink into the cushion 4. The metatarsal bones are prevented from crowding by being supported at the rear of 110 the ball of the foot.

It will thus be seen that by my improved 115 insole cushioning is provided at the points required, while at the same time the grip of the toes is not interfered with and the possibility of wrinkles or lumps forming on the cushioning portion of the insole is eliminated.

nated, thereby contributing to the comfort and service of the shoe. When the weight of the body is applied to the foot the resilient areas in the insole are depressed beneath the 5 weight bearing points and the other areas of the bottom of the foot are thereby brought into proper contact with the non-resilient area of the insole thereby permitting a proper distribution of the weight throughout 10 the contact areas of the foot.

With the use of my invention not only is the shock incident to walking on hard pavements absorbed but a cushioned insole is provided which correctly conforms to the anatomy 15 of the foot. My invention by providing proper contact at the heel insures the proper distribution of the weight on either side of the weight bearing center line of the foot, thereby preventing strain on the ankle and 20 foot. With the use of my device unusual foot comfort is provided and walking is made more pleasurable.

What is claimed is:

1. A shoe insole comprising a non-resilient body conforming in shape to the sole of a shoe and formed with an opening in the heel portion and a second opening in the forward portion thereof, a resilient body positioned within said first named opening and 25 secured to said non-resilient body and arranged to extend substantially only beneath the downward extending portion of the os calcis, a second resilient body positioned within the forward portion of said last 30 secured to said non-resilient body, said last named resilient body being arranged to extend transversely of the insole and beneath the forward ends of the first and fifth metatarsal bones and to the 35 rear of the forward ends of the second, third and fourth metatarsal bones, and a harder body positioned within the rearward portion of said second named opening and secured to said non-resilient body and said 40 resilient body and extending beneath portions of all of said metatarsal bones rearward of their forward ends.

2. A shoe insole comprising a non-resilient body conforming in shape to the sole of a shoe and formed with a substantially triangular opening in the forward portion thereof beneath the metatarsal bones, the forward edge of said opening extending transversely of said sole, forwardly of the forward 45 ends of the first and fifth metatarsal bones and rearwardly of the forward ends of the second, third and fourth metatarsal bones, and a triangular shaped member positioned within said opening, the forward portion of 50 said member being resilient and its rearward portion being relatively hard, said relatively hard portion extending under the forward portion of all the metatarsal bones rearwardly of their forward ends.

65 3. A shoe insole comprising a non-resil-

ient body conforming in shape to the sole of a shoe and formed with an opening below the metatarsal bones, the forward edge of said opening extending transversely of said sole, forwardly of the forward ends of the first and fifth metatarsal bones and rearwardly of the forward ends of the second, third and fourth metatarsal bones, and a resilient body positioned within said opening.

In testimony whereof I affix my signature. 75
JOHN FENTON.
